UNITED STATES PATENT OFFICE

2,454,365

WEED BURNING APPARATUS

Horace E. Woolery, deceased, late of St. Paul, Minn.; by Myra Lillian Woolery, executrix, St. Paul, Minn., assignor to Woolery Machine Company, Minneapolis, Minn., a corporation of Minnesota

Application January 26, 1946, Serial No. 643,714

6 Claims. (Cl. 126—271.2)

1

This invention relates generally to improvements in weed burning apparatus for use by railroads and others in burning weeds, clearing ditches and the like.

The primary object of the present invention is to provide a light, compact and sturdy frame assembly for the component parts of such an apparatus, such as the engine, blower, fuel oil pump and burner head. Another object is to provide an improved mechanism for easily raising and lowering the burner head and for holding the head in any adjusted position. Still another object is to provide a weed burning assembly in a form which is applicable to many installations, such as upon a wheeled railway car or a truck and which therefore has a wide range of uses on railways along canals and ditches, or for ice removal, thawing frozen pipes or areas to be excavated, and many other uses.

The present application is a continuation in part from the copending application of Horace E. Woolery, Serial No. 486,973, for Weed burner, filed May 14, 1943 now Patent 2,452,411, October 26, 1948.

These and other more detailed and specific objects will be disclosed in the course of the following specification, references being had to the accompanying drawings, in which—

Fig. 1 is a side elevation of the apparatus.

Fig. 2 is an enlarged end and sectional view along the line 2—2 in Fig. 1.

Fig. 3 is an enlarged fragmentary side view, partially broken away and in section particularly showing the brake for holding the burner head in adjusted positions.

Referring now more particularly and by reference characters to the drawing A designates generally a conventional burner assembly such as also disclosed in the co-pending application hereinbefore referred to and including a blower B and engine C. The burner further includes a burner head or flame projector D at the end of a long burner tube E swingably connected at F to a tube G leading from the blower B. The arrangement is such that the head D may be swung upwardly or downwardly in an upright plane so as to vary the height of the flame with respect to the weeds or the surface of the ground.

For supporting and adjusting the foregoing mechanism the present invention provides a compact, light and strong base or basic frame assembly made up of suitable steel shapes all riveted, welded or otherwise suitably connected to form a rigid structure. This frame comprises base angles or sill members 10 set up in parallel fairly

2

closely spaced relation and rigidly joined by a base plate 11, (or series of suitably arranged narrow strips) upon which the blower B, engine C and other parts may be conveniently bolted. The frame further includes four upright corner posts 12 secured at lower ends to the ends of the sill members 10 and extending upwardly in converging relation in a transverse plane therefrom. The closely spaced upper ends of the corner posts 12 are thus readily attachable to opposite sides of a truss-like upper frame 13 as indicated at 14. Said frame 13 is formed of upper and lower channels or channel-shaped bars 15 and 16 between which is arranged and welded a truss strip 17, and the frame extends in the form of an outrigger portion or boom 18 out beyond the corner posts 12 at one end of the assembly, over the burner tube E. The upper and lower bars 15 and 16 converge in a vertical plane toward this end of the frame 13 and are joined by bearing plates 19 between which is journaled a pulley or roller 20. At their opposite ends, toward which they also converge, the bars 15 and 16 are joined by bearing plates 21 through which is transversely journaled a shaft

22.

A sprocket chain 23 is attached at one end by a coupler link 24 to the burner head D and extends therefrom over the roller 20 and back along the top of the frame 13 and over a sprocket 25 secured to the shaft 22. The channel shape of the upper bar 15 provides a longitudinal upwardly opening guideway for the greater part of this length of the chain, as seen in Fig. 2 preventing lateral displacement of the chain. From the sprocket 25 the chain 23 is doubled back beneath the frame 13 and passed over a pulley or roller 26 connected at 27 to the end of a tension spring 28, and the chain is then again doubled back or looped and its extremity finally fastened to a pin 29 which extends through and between the posts 12 below the shaft 22. The opposite end of the spring 28 is secured at 30 to the extremities of bracket bars 31 secured to the posts 12 and extending therefrom out beneath the boom portion 18 of the frame 13. These bars 31 are connected to the boom 18 by depending hanger bars 32.

The shaft 22 may be rotated by a hand wheel 33 secured to one end of the shaft, and to its other end there is fastened a grooved pulley 34 and cooperating with said pulley is a bell-crank shaped brake lever 35 fulcrumed on one end of the aforesaid pin 29 and having two opposite handle ends or arms 37. One of such arms 37 has attached thereto a brake shoe 38 (Fig. 3) adapted to enter the peripheral groove 39 in the pulley

34 and to the other arm there is attached a retractile coil spring 40 which is connected at 41 to the frame 13. This spring normally biases the lever 35 in a direction such that the brake shoe 38 will enter the pulley groove and so frictionally lock the shaft 22 against rotation. However, by grasping either arm 37 of the lever and pulling to the right, as viewed in the drawing, the brake shoe will be swung clear enough so that the shaft may be turned by the hand wheel 33. Diagonal bracing to support the angular pull on the frame by weight of the burner head is provided by brace bars 42 connecting the posts 12 and sills 10 as seen in Fig. 1.

The operation of the burner mechanism will no doubt be apparent. The burner head may be raised and lowered as required by releasing the brake as described and turning the hand wheel 33 which will, of course, turn the sprocket 25 and so pay out the chain and lower the head or draw in the chain and raise it. As the burner head is lowered the spring 28 is put under increasing tension and the force thus stored will assist in raising the head so that little effort is required by the operator. The brake mechanism will also thus hold the burner head in any selected vertical position.

The narrow, rectangular flat base of the frame assembly makes it convenient to mount and support upon any desired form of transport vehicle and it will be evident that the entire structure is very compact and strong.

It is understood that suitable modifications may be made in the structure as disclosed, provided such modifications come within the spirit and scope of the appended claims. Having now therefore fully illustrated and described the invention, what is claimed to be new and desired to protect by Letters Patent is:

1. In a weed burning apparatus having an extending vertically swingable flame projector adjustable with respect to the forward end of a boom, means for raising and lowering the flame projector including a pulley at the outer end of the boom, a shaft at the rear end of the boom, a sprocket on said shaft, a chain connected at one end to the flame projector and trained over said pulley and sprocket, a spring anchored at one of its ends to the boom and having a movable connection at its opposite end to the chain to counterbalance the weight of the flame projector, and means for rotating the shaft and sprocket to raise and lower the flame projector.

2. In a weed burning apparatus having an extending vertically swingable flame projector adjustable with respect to the forward end of a boom, means for raising and lowering the flame projector including a pulley at the outer end of the boom, a shaft at the rear end of the boom, a sprocket on said shaft, a chain connected at one end to the flame projector and trained over said pulley and sprocket, a spring anchored at one of its ends to the boom and having a movable connection at its opposite end to the chain to counterbalance the weight of the flame projector, means for rotating the shaft and sprocket to raise and lower the flame projector, and brake means for releasably locking the shaft to hold the flame projector in any adjusted position.

3. In a weed burning apparatus having an extending vertically swingable flame projector adjustable with respect to the forward end of a boom, means for raising and lowering the flame

projector including a pulley at the outer end of the boom, a shaft at the rear end of the boom, a sprocket on said shaft, a chain connected at one end to the flame projector and trained over said pulley and sprocket, a spring anchored at one of its ends to the boom and having a movable connection at its opposite end to the chain to counterbalance the weight of the flame projector, means for rotating the shaft and sprocket to raise and lower the flame projector, and brake means for releasably locking the shaft to hold the flame projector in any adjusted position, said brake means comprising a peripherally grooved pulley secured to the shaft, a pivoted brake lever having a brake shoe for engaging the pulley groove and spring means biasing the brake lever and to urge the brake shoe into frictional engagement with the pulley groove.

4. In a weed burning apparatus having an extending vertically swingable flame projector adjustable with respect to the forward end of a boom, means for raising and lowering the flame projector including a pulley at the outer end of the boom, a shaft at the rear end of the boom, a sprocket on said shaft, a chain connected at one end to the flame projector and trained over said pulley and sprocket, a spring anchored at one of its ends to the boom and having a movable connection at its opposite end to the chain to counterbalance the weight of the flame projector, means for rotating the shaft and sprocket to raise and lower the flame projector, brake means for releasably locking the shaft to hold the flame projector in any adjusted position, said brake means comprising a peripherally grooved pulley secured to the shaft, a pivoted brake lever having a brake shoe for engaging the pulley groove and spring means biasing the brake lever and to urge the brake shoe into frictional engagement with the pulley groove, the said brake lever being bell crank-shaped and having two handle ends.

5. In a weed burning apparatus having an extending vertically swingable flame projector adjustable with respect to the forward end of a boom, means for raising and lowering the flame projector including a pulley at the outer end of the boom, a shaft at the rear end of the boom, a sprocket on said shaft, a chain connected at one end to the flame projector and trained over said pulley and sprocket, a spring anchored at one of its ends to the boom and having a movable connection at its opposite end to the chain to counterbalance the weight of the flame projector, means for rotating the shaft and sprocket to raise and lower the flame projector, and means for guiding the run of the chain between the pulley and sprocket.

6. In a weed burning apparatus having an extending vertically swingable flame projector adjustable with respect to the forward end of a boom, means for raising and lowering the flame projector including a flexible element attached at one end to the flame projector adjacent its upper swinging end, rotatable members for guiding the flexible element, one of said members being mounted on a fixed axis, means to rotate said last named member to actuate the flexible element, another of said rotatable members being spring-supported for tensioning the flexible element for counterbalancing the weight of the flame projector and releasable brake means acting on the rotatable guide member on the fixed axis for restraining lineal movement of the flexible ele-

ment and operating to hold the flame projector in any height-adjusted position.

MYRA LILLIAN WOOLERY,
Executrix of the Last Will and Testament of 5
Horace E. Woolery, Deceased.
